UNITED STATES PATENT OFFICE.

ELMER E. TAYLOR, OF ST. LOUIS, MISSOURI.

HAIR-PIN.

1,209,357.

Specification of Letters Patent. Patented Dec. 19, 1916.

Application filed September 6, 1916. Serial No. 118,671.

To all whom it may concern:

Be it known that I, ELMER E. TAYLOR, a citizen of the United States, and a resident of St. Louis, in the State of Missouri, have 5 invented certain new and useful Improvements in Hair-Pins, of which the following is a specification.

My invention relates to hairpins, and one of the main objects thereof is to provide 10 such devices which will not be accidentally dislodged, which may be readily withdrawn, and which will not injure the hair.

My invention is fully described in the following specification, of which the accompanying drawing forms a part, said drawing 15 being an elevation of the hairpin, partly in section to show a detail of the construction.

Referring to the drawing, 1 represents a 20 length of wire bent at 2 to provide two legs 3 and 4 pointed at their ends, each leg consisting of two members 5 and 6 telescoped one upon the other, and spring bows 7 and 8 which yield under slight pressure into flat- 25 tened positions, or substantially so, whereby the legs may be passed readily between the strands of hair, said bows automatically assuming their normal bowed form when the pin is in place, thereby preventing the acci- 30 dental removal thereof.

The telescoped portions of the legs serve

to maintain the legs straight, in view of the fact that the bows are made very light, and the said telescoped portions slide one upon the other in the compression or expansion of the bows. 35

My hairpin is very simple though highly efficient and as no barbs or equivalent are presented to the hair the latter is not injured by my hairpin and, while I have shown 40 a preferred form, I may modify the same within the scope of the appended claims.

Having fully described my invention, what I claim as new, and desire to secure by Letters Patent is:— 45

1. A hairpin consisting of a length of wire bent into a loop to form legs in substantial parallelism, spring bows on each leg yielding under pressure into flat form, each leg being interrupted in the position of said 50 bows to permit such bow action, and means forming a part of each leg and arranged between the respective bows for preventing the flexing of the axes of said legs in the positions of said bows. 55

2. A hairpin consisting of a length of wire bent into a loop to form substantially parallel legs each of which is formed of two telescoped members joined by oppositely ar- 60 ranged spring bows.

ELMER E. TAYLOR.
